BOBBIN SUPPORT FOR WEFT-REPLENISHING LOOMS.

Application filed August 6, 1925. Serial No. 48,627.

This invention relates to improvements in bobbin supports for weft replenishing mechanism more particularly of the multi-color type and an object of the invention is to 5 provide a giveway having an end yieldable in all angular directions with respect to the axis of the supporting structure.

In co-pending application Ser. No. 47,145 there is shown a giveway or bobbin support 10 made of tubular sections one of which is held rigidly in place and the other of which has mounted thereon a yieldable nose located under the transerrer mechanism, the tubular sections being relatively yieldable. In 15 said application two springs are mounted within the tubular members one being smaller and weaker than the other and it is possible for one spring to interfere with the action of the other. It is a further object 20 of our present invention to place the stronger of these springs on the outside of the tubular members so that the weaker spring may be free to operate without interference.

It is a still further object of our invention 25 to provide a pair of tubular members held together by a comparatively strong coil spring which frictionally engages both members to permit yielding of the same and has the outer diameter thereof substantially the 30 same as the diameter of the sections so as to present a smooth surface down which a bobbin may roll to transfer position.

With these and other objects in view which 35 will appear as the description proceeds, our invention resides in the combination and arrangement of parts hereinafter described and set forth in the claims.

In the accompanying drawings wherein 40 we have shown a convenient form of our invention,

Fig. 1 is a transverse vertical section through a multi-color weft replenishing mechanism having our invention applied thereto,

Fig. 2 is an enlarged vertical longitudinal section through the giveway showing the supporting structure therefor,

Fig. 3 is a section on line 3-3 of Fig. 2, and

Fig. 4 is a section on line 4-4 of Fig. 2.

Referring to the drawings it will be seen that we have provided a weft replenishing frame 10 having vertical guides 11 in which bobbins are normally disposed as they await transfer. The frame has cast thereon a 55 guide 12 and has movably mounted thereon a support 13 which is pivotally mounted on the lower end of a link 14 loose on a tie rod 15. Said support 13 has a rearwardly and upwardly extending arm 16 which is connected as at 17 to a link 18 pivotally mounted to the frame as at 19. A spring 20 serves to hold the support or giveway 13 in normal position. The matter thus far described is of common construction and may be the same 60 as that shown in Patents No. 1,030,748 and No. 1,366,950.

Our improvements relate to the outer giveway on which normally rests the cylindrical portion of the yarn on the bobbin 70 awaiting transfer. As shown in Patent No. 1,518,892 the outer rear bobbin support engages the yarn between the conical portions thereof and the butt of the bobbin and it is to be understood that our improved support 75 is to be used in the manner as set forth in said patent, although it may also be used satisfactorily to support the wooden tip of the bobbin. In carrying out our invention we provide a bracket 30 fastened to a tie 80 rod 15 by means of screw 31 and split as at 32 to provide a clamp which may be tightened by screws 33. The bracket may be adjusted to any angular position and has secured therein a tubular section 34 having a 85 reduced forward end 35. A second tubular section 36 is also provided with a reduced rear end 37 substantially the same diameter as the end 35 and is held in alignment therewith by a coil spring 38 frictionally held to 90 the reduced ends and abutting shoulders 39 and 40 formed on sections 34 and 35, respectively. In order to prevent the spring 38 from being accidentally displaced the same is wound so that the internal diameter thereof is somewhat less than the outside diameter of the reduced end portions 35 and 37.

By means of the construction already described it will be seen that the section 36 is held yieldingly with respect to section 34. 100

Extending forwardly from the section 36 is a bobbin supporting nose 41 the rear portion of which is the same diameter as the tubular section 36. Said nose is held against 5 the latter section yieldingly by means of a spring 42 which is connected to an eye 43 formed in the rear end of nose 41 and is held under tension by a screw 44 to which it is attached. Said screw is threaded through 10 a cap 45 held to the rear end of the section 34 in adjusted position by means of screws 46. The spring 42 is weaker than the spring 38 so that under normal transfer conditions the nose 41 will yield without causing relative movement of the tubular sections.

It occasionally happens that a bobbin will be so slow in arriving at transfer position as to be engaged by the transerrer 47 while the bobbin is still on section 36. When this 20 happens the said section will move to the dotted line position shown at 60 by the yielding of spring 38. On the other hand should the transfer be improper so that a portion of the bobbin projects above the 25 shuttle to engage the nose 41 the latter will be moved upwardly to the dotted line position shown at 70 in Fig. 2. It will be noticed that the exterior surfaces of the several parts of the giveaway present a substantially smooth and uninterrupted surface 30 down which the ribbon may roll and at the longitudinal position of the support may be adjusted by means of screw 32 on the bracket 30.

From the foregoing it will be seen that 35 we have provided a simple form of bobbin support having the movable portions thereof yieldable in all angular directions with respect to the supporting structure and having the weaker spring which holds the nose 41 in normal position located inside the tube 40 where it is out of contact with the spring 38 and that the latter spring frictionally engages the sections 34 and 36 to hold the same 45 together and in substantial alignment.

Having thus described our invention it will be apparent that changes and modifications may be made therein by those skilled 50 in the art without departing from the spirit and scope of the invention, and we do not wish to be limited to the details herein disclosed, but what we claim is:

1. In a weft replenishing mechanism for 55 looms, an angularly adjustable holding means mounted on the mechanism, a bobbin support carried thereby and formed of a pair of sections, and a coil spring frictionally engaging exterior portions of the sections to permit yielding relative motion 60 of said sections.

2. In a weft replenishing mechanism for 65 looms, a supporting structure mounted on and angularly adjustable with respect to the mechanism, a bobbin support comprising a pair of tubular sections one of which

is held by the supporting structure, adjacent portions of said tubular sections being reduced in diameter, and a coil spring frictionally engaging the reduced adjacent portions of the tubular sections to support 70 the other of said sections for angular motion in all directions with respect to the supported sections, the outside diameter of the spring being substantially the same as the diameters of the unreduced portions of 75 said sections.

3. In a weft replenishing mechanism, supporting structure mounted on and angularly adjustable with respect to the mechanism, and a hollow bobbin support having 80 two sections, yieldable means attached to the outer portions of the sections, a bobbin supporting nose adjacent one of said sections, and yielding means passing through the sections for holding said nose in normal position.

4. A bobbin support for loom weft replenishing mechanism comprising a pair of tubular sections having reduced adjacent portions, and a coil spring the inside diameter of which is less than the outside diameter of the reduced portions of said sections, 90 said spring being frictionally mounted on the reduced sections.

5. A bobbin support for loom weft replenishing mechanism comprising a pair of tubular sections, a spring frictionally engaging the exterior portions of the tubular sections, a nose located adjacent one of said tubular sections, and a spring located within the sections and connected to the nose to hold the latter in normal position, the last named spring being weaker than the first named spring and being spaced from the latter by portions of the tubular sections. 100

6. In a weft replenishing mechanism for looms, a holder fixed relatively to the mechanism, a bobbin support mounted on the holder, said support having a portion held to the holder and another portion to engage 110 a bobbin, and a spring having holding contact with the exterior of the portions to hold the bobbin engaging portion yieldable relatively to the portion held by the holder.

7. A bobbin support for a loom weft replenishing mechanism, said support comprising a pair of members one of which is formed for cooperation with supporting structure and the other member of which engages a bobbin, said support further including a resilient device having holding contact with a portion of the exterior of each member to hold said bobbin engaging member yieldable relatively to the first named member. 115

8. In a weft replenishing mechanism for looms, a bobbin support a portion of which is held rigidly with respect to the replenishing mechanism and has a surface along which a bobbin may roll, a second portion 120

for the support also having a surface along which a bobbin may roll, and a resilient device engaging part of the exterior of each portion of the support to connect said portions together and afford a yielding mounting for the second named portion, said resilient device having a bobbin engaging sur-

face in substantial alignment with the surface of said portions along which a bobbin may roll.

10

In testimony whereof we have hereunto affixed our signatures.

CHARLES M. ERLER.
